UNITED STATES PATENT OFFICE.

MOÏS H. AVRAM, OF NEW YORK, N. Y., ASSIGNOR TO AVRAM-LEET ENGINEERING COMPANY,
OF NEW YORK, N. Y., A CORPORATION OF NEW YORK.

PRESS.

No. 866,999.

Specification of Letters Patent.

Patented Sept. 24, 1907.

Application filed November 14, 1906. Serial No. 343,341.

To all whom it may concern:

Be it known that I, Moïs H. AVRAM, a citizen of the United States, residing at the city, county, and State of New York, have invented certain new and useful 5 Improvements in Presses, of which the following is a full, clear, and exact description.

My invention relates to improvements in presses, and has for its object to produce a simple and efficient press for molding articles such, for instance, as bricks. 10 It further has for its object to produce a press which will be rapid in its action and produce a uniform product.

One of the principal objects of my invention is to provide a press having a stationary mold table, and 15 also to provide a movable feed slide which shall coöperate with the stationary mold table.

Another object is to provide a feed slide located below a stationary mold table, and means for feeding the material to be compressed upward into the mold table.

20 Another object of my invention is to provide automatic ejecting and receiving mechanism.

The following is a description of my invention, reference being had to the accompanying drawings, in which,

25 Figure 1 shows a side elevation of my press partly in section. Fig. 2 shows a vertical central section of the same. Fig. 3 shows diagrammatically the pipe system and valves and the cams for operating the valves, and slides.

30 The drawings show a double acting duplex press, the two parts being duplicates of each other.

Referring more particularly to the drawings, A represents a stationary mold table supported by four uprights B and having two sets of mold openings A² A³, 35 whose width and length correspond to the height and length of a brick to be formed, that is, to the largest and smallest dimensions of the brick. These uprights B are carried by four lower hydraulic cylinders C and C', and in turn support the upper hydraulic cylinders D 40 and D'. Between each set of the upper hydraulic cylinders D D' is a feed hopper E, the lower part of which is formed by a central opening E' in the table A.

F F' are feed slides each having openings G G' shown in the drawings as filled with material to be compressed.

45 One of these openings registers with the discharge opening E' of the hopper E when the other registers with one of the mold openings A² A³. The feed slide carries two upwardly movable plungers H H' adapted to be actuated by rams I I' in the lower hydraulic cylinders C C'. The slide also carries two receiving tables J J', which are engaged by segments K K', which segments are provided with counterweights, or equivalent devices, L L', tending to keep the receiving tables on a line with or near the bottom of the mold table A 50 when the receiving tables are empty.

The plungers H H' are provided with T-shaped heads H H', which are engaged by undercuts i i' on the upper ends of the rams I I', so that when the rams I I' are moved downwardly they forcibly draw the plungers downward.

60

The rams of the upper hydraulic cylinders D D' are provided with dies D² D³ which enter the mold openings A² A³ in the mold table as shown.

D⁴ are drip basins carried by the upper rams.

The main shaft M carries segmental gears N N', journaled at N² which engage with racks N³ on the lower sides of the feed slides F F'. These segmental gears have anti-friction rollers O which travels in grooves P in a cam Q mounted upon the main shaft, and are thereby given a reciprocating motion, resulting in a 70 reciprocating motion of the feed slides.

65

The upper hydraulic cylinders D' D' are connected to a common supply pipe controlled by a hydraulic valve R, which is actuated by a pitman controlled by the cam groove s' on the reverse side of the cam S' upon 75 the main shaft. The upper cylinders D D' are similarly connected to a common supply controlled by a valve through the cam S'. The lower hydraulic cylinders are provided with ports T T, which when connected to a supply of pressure admit water to raise the 80 rams, and also the ports U U, which when connected to the supply pressure admit water to depress the rams. These ports in the cylinders C' C' are controlled by a reversing hydraulic valve V, which is actuated by a cam groove s² on the reverse side of the cam S'. 85

The cam grooves s' and s² are so constructed and timed that the valve R controlling the upper ram is open to discharge, while the valve V controlling the lower piston is open to pressure beneath the ram. The result is, that the lower ram forces the contents of one 90 of the openings in the feed slide up into a mold table opening, and simultaneously raises the corresponding upper ram. This action gives to the material forced into the mold table a preliminary pressure. When the lower ram has reached its upward limit, the valve 95 V controlling the supply of water to its cylinder is moved by its actuating cam groove s² so as to close both the inlet and outlet ports, thus positively locking the lower ram. At this time the upper hydraulic cylinder is connected to pressure through its hydraulic valve R, and exerts a downward pressure which is the 100 final pressure and may be made as great as desired, depending on the source from which it is derived. After this final pressure is exerted, the upper hydraulic cylinder is cut off from the supply and the 105 chamber below the lower ram is opened to discharge and pressure is admitted above the piston so that the lower ram descends. During the period immediately following, the cam Q acts to move the feed slide F so that the opening G' registers with the mold opening 110

- A³, and the receiving table J carried by the feed slide F comes beneath the mold opening A². The hydraulic valve R controlling the upper cylinder is then again opened to pressure and the downward movement of the upper ram resumed, resulting in the ejection of the compressed material upon the receiving table J. The receiving table J being counterbalanced by a weight L is depressed as the compressed material is ejected, and the weight of the compressed material causes it to descend to its lowest position. The feed slide opening G has now received a fresh supply of material from the hopper E and the slide is again reciprocated so that the opening G registers with the mold opening A². This moves the receiving table J away from beneath the mold table, whereupon the compressed material is removed from the receiving table by hand or otherwise. The receiving table is then lifted by its counterbalance L so as to be ready to receive another brick, when it is again moved beneath the mold table openings and another brick is ejected. The cycle of operations for the rams, slide openings G' and receiving table J' at the other end of the press is similar to the cycle of operations just described, but as the valve actuating cam grooves of the cam S' are displaced by 180° each step is half a period later than the corresponding step as carried out in the other half of the press.

In Fig. 3 the pipe and valve connections for cylinders at one end are shown. The arrangements for the two ends are relatively the same except that the cams S S' controlling the cylinders at opposite ends are displaced by 180°. If desired the cylinders of either half of the press can be cut out of action by the valves Y.

In Figs. 1 and 2 the press is in position where the contents of the mold opening A³ are about to be expelled, and the contents of the feed opening G about to be forced into the mold opening A².

In Fig. 3 the cam grooves s' s² are in positions such that the valve R is opened to pressure and the contents of a mold opening is undergoing final pressure. The valve V is closed so as to hold the lower piston fixed. The high level a b of the groove s² corresponds to the upward movement of the lower ram. The high level b² c² of the groove s' corresponds to the downward final pressure of the upper ram. The intermediate level b c of the groove s² corresponds to the locked position of the lower ram which is its condition when the upper ram is exerting final pressure. The low level c d corresponds to the withdrawing position of the lower ram. The high level e² f² corresponds to the downward ejection movement of the upper ram. The high level a' d' and the low level e' g' of the cam P correspond to periods of rest of the slides F F'. When the valves R and V are in the positions shown the roller O is in the center of one of the levels of the cam groove P, as shown in Fig. 3.

The hydraulic valves R and V are located at any convenient points, there being as shown in Fig. 3 one valve for each pair of cylinders. Their inlets are connected to any suitable sources of hydraulic pressure.

The apparatus is accurate and rapid in its operation. Only one brick being compressed at a time, all the bricks receive the same pressure and are compressed to the same density. The advantage of having the mold table stationary is very great, since it is subjected to great strain, and by making it stationary the parts can

be stronger and more durable. The feed slide does not require such careful mounting or accurate action, and therefore can be made movable with much greater safety than the mold table. The upward feed permits of a downward delivery without removing the upper plungers from the mold openings. The counterbalanced receiving tables provide for the safe delivery of the compressed articles and are entirely automatic in their action.

One important feature in my press is that the contents of the mold is given a preliminary pressure as well as a final pressure without moving the mold table relatively to the axis of the compressing plungers; another feature is that the contents of the mold opening is subjected to preliminary pressure while the mass as a whole is moving in the mold opening, that is while the upper ram is being forced upward by the lower ram. This bodily movement during preliminary compression enables the air to escape more readily along the walls of the opening. Another important feature of my invention is that the pressure is not applied to the brick in the direction of its smallest dimension. Thus in my press the pressure is applied to the sides of the brick. This results in a more general distribution of any irregularities in the material fed into the mold opening, and also makes the path for the escape of air bubbles along the compressed surface shorter than it would be if the pressure was applied to the top and bottom of the brick. Moreover the pressure per square inch to which the brick is subjected is greater for a given hydraulic pressure than it would be if the pressure were applied to the larger areas of the top and bottom.

A press exerting pressure on the sides of the brick has the further advantage of producing a brick whose most important surface, *i. e.* the side which is exposed when in a wall, is absolutely uniform in size. When pressure is applied to the top of a brick by a hydraulic plunger, the stroke of the plunger will vary somewhat, so that the brick will vary in thickness. When the hydraulic pressure is applied to the side of the brick, the width of the brick may vary, although the length and thickness will always be the same. Variation in either length or thickness is important, while variation in width is immaterial since the side-pressed brick when used is always apparently, if not actually, uniform.

My invention permits of various modifications embodying my broad ideas here set forth, without departing from the spirit of my invention.

What I claim is:

1. In a press the combination of a stationary mold table having a mold opening, a movable feeding member located beneath said table, and an upwardly acting plunger adapted to force material to be pressed from said feeding member into said mold opening.
2. In a press, the combination of a stationary mold table having a mold opening, a feed hopper, a reciprocating feed slide located below said mold table, and a plunger adapted to force the contents of said feed slide upward into said mold opening and compress it.
3. In a press, the combination of a stationary mold table having a mold opening, a movable feeding member located beneath said table, and an upwardly acting plunger adapted to force material to be pressed from said feeding member into said mold opening, and a downwardly acting plunger adapted to eject the contents of said mold opening.
4. In a press, the combination of a stationary mold table

having a mold opening, a movable feeding member located beneath said table, and an upwardly acting plunger adapted to force material to be pressed from said feeding member into said mold opening, and a downwardly acting plunger adapted to exert a final pressure upon, and then eject the contents of said mold opening.

5. In a press the combination of a stationary mold table having a mold opening, a movable feeding member located beneath said table, and an upwardly acting plunger adapted to force material to be pressed from said feeding member into said mold opening and exert thereon a preliminary pressure upon, and a downwardly acting plunger adapted to exert a final pressure upon, then eject the contents of said mold opening.

10. 6. In a press, the combination of a stationary mold table having mold openings at its respective ends, a feeding slide supplying material to be compressed to said mold openings alternately; means for reciprocating said slide, and means for compressing the contents of the mold openings successively.

15. 7. In a press, the combination of a stationary mold table having mold openings at its respective ends, a feed hopper, a reciprocating feed slide having openings, one adapted to register with a mold opening and the other with the feed hopper at the end of each reciprocation, means for reciprocating said feed slide, and plungers adapted to force the contents of said slide into said mold openings and compress such contents.

20. 8. In a press, the combination of a stationary mold table having mold openings at its respective ends, a feed hopper, a reciprocating feed slide located below said mold table, low pressure plungers adapted to force the contents of said feed slide upward into said mold openings and compress it, and high pressure plungers adapted to exert a downward and final pressure on said contents.

25. 9. In a press, the combination of a stationary mold table having mold openings at its respective ends, a feed hopper, a reciprocating feed slide located below said mold table, low pressure plungers adapted to force the contents of said feed slide upward into said mold openings and compress it, high pressure plungers adapted to exert a downward and final pressure on said contents, receiving means, and means for causing said high pressure plungers to eject said contents when compressed.

30. 10. In a press, the combination of a stationary mold table having mold openings at its respective ends, a feed hopper, a reciprocating feed slide located below said stationary mold table, upwardly acting plungers carried thereby and adapted to force the contents of said feed slide upward into said mold openings and compress it.

35. 11. In a press, the combination of a stationary mold table having a mold opening, a downwardly acting plunger for compressing the contents of said mold opening, means located below said table for receiving the contents of said mold opening, and means for causing said plunger to eject said contents from said mold opening.

40. 12. In a press, the combination of a stationary mold table, a reciprocating feed slide, a vertically movable receiving table carried by said slide, means for forcing material to be compressed from said slide into said mold openings, and means for compressing said material within said mold openings and ejecting it upon said receiving table.

45. 13. In a press, the combination of a stationary mold table, a feed slide located beneath said mold table, means for reciprocating said slide, a vertically movable receiving table carried by said slide, means for forcing material upward from said slide into said mold openings when said slide is at the end of a movement in one direction, means for finally compressing said material, and means for ejecting said material upon said receiving table when the slide is at the end of its movement in the other direction.

50. 14. In a press, the combination of a stationary mold table having a mold opening, a feed slide located beneath said table, means for reciprocating said slide, a receiving table carried by said slide, a feed hopper, said slide having an opening adapted to register alternately with said mold

opening and said feed hopper, said receiving table being beneath said mold opening when said slide opening is in register with said hopper, means for forcing the contents of said slide opening into said mold opening and compressing it therein while said slide opening registers with said mold opening, and means for ejecting said contents upon said receiving table while said slide opening is in register with said feed hopper.

55. 15. In a press, the combination of a stationary mold table having a mold opening, a feed slide located beneath said table, means for reciprocating said slide, a receiving table carried by said slide, a feed hopper, said slide having an opening adapted to register alternately with said mold opening and said feed hopper, said receiving table being beneath said mold opening when said slide opening is in register with said hopper, means for forcing the contents of said slide opening into said mold opening and compressing it therein while said slide registers with said mold opening, means for ejecting said contents upon said receiving table while said slide opening is in register with said feed hopper, and means for holding said receiving table when empty near the bottom of said mold table.

60. 16. In a press, the combination of a stationary mold table having mold openings, a feed slide located beneath said table, means for reciprocating said slide and giving it periods of rest at the end of its movement in either direction, a receiving table carried by said slide, means for forcing material from said slide into said mold opening and also compressing it during one of the periods of rest of said slide, and means for ejecting the contents of said mold opening upon said receiving table during the next period of rest of said slide.

65. 17. In a press, the combination of a stationary mold table having mold openings, a feed slide located beneath said table, means for reciprocating said slide and giving it periods of rest at the end of its movement in either direction, a lower plunger acting to force material from said slide into one of said mold openings and give it preliminary pressure during one period of rest and an upper plunger adapted to give said material final pressure during the same period of rest and to eject said material during the next period of rest of said slide.

70. 18. In a press, the combination of a stationary mold table having mold openings, a feed slide located beneath said table, means for reciprocating said slide and giving it periods of rest at the end of its movement in either direction, receiving tables carried by said slide, a lower plunger acting to force material from said slide into one of said mold openings and give it preliminary pressure during one period of rest, and an upper plunger adapted to give said material final pressure during the same period of rest and to eject said material upon one of said receiving tables during the next period of rest, said receiving tables being vertically movable and provided with means for holding them when empty near the bottom of said mold table.

75. 19. In a brick press, the combination of a mold table having a mold opening, an upper plunger and a lower plunger, a feed slide beneath said mold table, said lower plunger being adapted to force material to be pressed from said slide into said mold opening, against the yielding resistance due to the weight of said upper plunger.

80. 20. In a hydraulic brick-press, a mold table having a mold opening, the dimensions of said mold opening being equal respectively to the dimensions of the side face of the desired brick, that is to the largest and smallest dimensions of such brick, and a hydraulic cylinder connected with a source of pressure and a plunger therein exerting the same pressure on all bricks, said plunger having a single die, and the throw of said plunger within said mold opening being limited by the hydraulic pressure on said plunger and the amount of material within said mold opening.

MOIS H. AVRAM.
